CLAIM

The ornamental design for a pendant for sensory therapy, as shown and described.

DESCRIPTION

FIG. 1 is a front perspective view of a pendant for sensory therapy showing my new design;

FIG. 2 is a bottom view of the pendant for sensory therapy of FIG. 1;

FIG. 3 is a right side view of the pendant for sensory therapy of FIG. 1;

FIG. 4 is a top view of the pendant for sensory therapy of FIG. 1;

FIG. 5 is a left side view of the pendant for sensory therapy of FIG. 1;

FIG. 6 is a front view of the pendant for sensory therapy of FIG. 1; and,

FIG. 7 is a rear view of the pendant for sensory therapy of FIG. 1.

The broken lines shown in figures illustrate portions of the pendant for sensory therapy that form no part of the claimed design.
